(57) **CLAIM**

We claim the ornamental design for a pocket case for mobile communications devices combined with carrying compartment for credit card sized items, as shown and described.

DESCRIPTION

FIG. 1 is a back perspective view of a pocket case for mobile communications devices combined with carrying compartment for credit card sized items according to the present design.

FIG. 2 is a back elevation view thereof.

FIG. 3 is a front elevation view thereof.

FIG. 4 is a side elevation view thereof.

FIG. 5 is a side elevation view thereof, the side being the side opposite of the side shown in FIG. 4.

FIG. 6 is a top plan view thereof.

FIG. 7 is a bottom plan view thereof; and,

FIG. 8 is back perspective view thereof. The broken lines around the perimeter of the rear compartment depict stitching which is part of the claimed design. The outermost dot-dash broken line in FIG. 3, and the corresponding dot-dash broken line shown in each of FIGS. 4-7, represent a boundary of the claimed design. The innermost of the two dot-dash broken lines in FIG. 3 and the dash-dash broken lines throughout the figures depict unclaimed environment. The broken lines and surfaces that are visible through the openings in the case depict an unclaimed mobile communication device.
